UNITED STATES PATENT OFFICE.

ABRAHAM HESTER AND HENRY L. HESTER, OF CONCORD, MICHIGAN.

SHEEP-FEEDING DEVICE.

SPECIFICATION forming part of Letters Patent No. 284,301, dated September 4, 1883.

Application filed March 23, 1883. (No model.)

To all whom it may concern:

Be it known that we, ABRAHAM HESTER and HENRY L. HESTER, of Concord, in the county of Jackson and State of Michigan, have 5 invented new and useful Improvements in Sheep-Feeding Devices; and we hereby declare that the following is a full, clear, and exact description thereof, reference being had to the accompanying drawings, which form a 10 part of this specification.

This invention relates to certain new and useful improvements in the construction of sheep-feeding devices, by means of which the sheep may be fed with equal amounts of grain 15 to each, and prevented from crowding each other, or in one obtaining the feed properly belonging to another.

The invention consists in the peculiar construction of parts, and their combination, as 20 more fully hereinafter described.

Figure 1 is a perspective view of our improved device with a portion of the roof and wall broken away to show the stall-divisions and feed-trough. Fig. 2 is a top plan with 25 the cover of the grain-bin removed. Fig. 3 is a longitudinal vertical central section through the same.

In the accompanying drawings, A represents the roof, and B the end walls, of my feed- 30 stalls, said walls resting upon the ground or any suitable foundation.

C is a feed-trough extending the whole 35 length between the end walls, supported at a proper height for the sheep readily to feed therefrom.

D are partitions forming individual stalls, the distance between them being sufficient 40 to allow the sheep to reach the feed in the troughs, and sufficiently strong to prevent one sheep from crowding another while in the act of feeding. These partitions also, by extending forward transversely through the trough C, serve to divide said trough into compartments.

E is a board supported between the end 45 walls immediately over the trough, and sufficiently above the same to allow the sheep free access to the trough, and this board is provided with a series of holes vertically

through the same, and so arranged that each 50 division of the trough will have one of these holes discharging immediately therein.

F is a slide having a reciprocating motion by means of the lever G, and H is the bottom 55 of the feed-bin I, and this bottom is provided with a series of holes, b, corresponding with the holes in the slide F and board E. The slide F can be reciprocated between this bottom and the bar, and acts as a cut-off to prevent the feed from flowing out of the bin into 60 the trough except when the holes in the slide are coincident with the other delivery-holes described.

J is a rod, which also has a reciprocating motion given it by the throw of the lever G, and this rod extends longitudinally through the center of the feed-bin, and has attached thereto rake-heads c, or other suitable devices for moving the grain and preventing its packing in the bin, so that it will flow freely into 70 the trough below.

K is the front of the device, hinged to the roof, as shown. It must be raised to allow the sheep to enter, (each one its stall,) when it may be dropped to confine him in his position until he has completed his feed, and this hinged front will be found of great service in excluding snow or driving rain from the trough. The feed-bin itself is provided also with a hinged cover, L.

Should it be deemed desirable to duplicate 80 this device or provide for feeding sheep on each side with a central trough, it would simply be necessary to put a longitudinal division through the trough and duplicate the 85 holes in the delivery-board, slide, and bottom of the bin, so that each hole would deliver the requisite quantity of grain to each one of the divisions of the trough below.

What we claim as our invention is—
1. In a sheep-feeding device, a series of 90 stalls with roof A, supported on the stall-partitions, and cover K, hinged thereto, in combination with a trough subdivided into small compartments by the continuation of the stall-partitions D, a bin arranged above said trough and under a cover, as L; and means, substantially as described, for delivering the required

quantity of grain into each compartment of said trough simultaneously, as set forth.

2. In a feeding device, and in combination with a series of stalls with roof A and cover K, the trough C, divided into compartments by the stall-partitions D, the perforated board E, perforated slide F and lever G, the bin I, having perforated bottom and cover L, and

the rake-rod J and rake, all constructed, arranged, and operating as set forth.

ABRAHAM HESTER,
HENRY L. HESTER.
